UNITED STATES PATENT OFFICE.

JOHN H. PORTER, OF ATLANTA, GEORGIA.

FUEL-FEEDING APPARATUS.

1,142,364.

Specification of Letters Patent. Patented June 8, 1915.

Application filed March 20, 1913. Serial No. 755,699.

To all whom it may concern:

Be it known that I, JOHN H. PORTER, a citizen of the United States, residing at Atlanta, in the county of Fulton, State of Georgia, have invented certain new and useful Improvements in Fuel-Feeding Apparatus; and I do hereby declare the following to be a full, clear, and exact description of the invention, such as will enable others skilled in the art to which it appertains to make and use the same.

This invention relates to fuel feeding apparatus and particularly to an apparatus for feeding pulverized coal to a furnace.

15 The object of the invention resides in the provision of an apparatus of the type named which will deliver an even flow of pulverized fuel to the furnace, and distribute same over a wide area within the furnace.

20 A further object of the invention resides in the provision of a fuel feeding apparatus which includes means for mingling a proper proportion of air with the pulverized coal as same is delivered to the furnace so as to 25 secure an efficient combustion.

With the above and other objects in view the invention consists in the details of construction and in the arrangement and combination of parts to be hereinafter more 30 fully described and particularly pointed out in the appended claim.

In describing the invention in detail reference will be had to the accompanying drawings wherein like characters of reference denote corresponding parts in the several views, and in which—

Figure 1 is a vertical section of a fuel feeding apparatus constructed in accordance with the invention and showing same operationally applied to a furnace; Fig. 2, a plan view of the apparatus partly in section; Fig. 3, a section on the line 3—3 of Fig. 1; Fig. 4, a section on the line 4—4 of Fig. 2; Fig. 5, a section on the line 5—5 of Fig. 2, and Fig. 6 a detail perspective view showing the construction for adjusting the slide valve which controls the feed of the coal.

Referring to the drawings A indicates the front wall of a furnace which is provided with a fuel feed opening 10 all of the usual and well known construction. Supported on the front wall A on each side of the opening 10 is a bracket 11 and supported upon the outer ends of these brackets 11 is 65 a casing B having an open upper end 12 whereby fuel may be supplied to the in-

terior of the casing in any desired manner. The casing B is provided at its lower end with a lateral enlargement 13 of substantially semi-cylindrical shape and directed toward the wall A. Projecting from the lower end of the enlarged portion 13 and communicating with the interior of the casing B is a horizontal chute 14. This chute is of tubular form and has its outer end disposed relatively near the opening 10 so that fuel discharging therefrom will be delivered to the interior of the furnace. Mounted in the outer end of the chute 14 is a plurality of distributing plates 15, the central plates 15 being disposed longitudinally of the chute, while the outer ends of the remaining plates are directed outwardly toward the adjacent side of the chute. By this construction it will be apparent that fuel discharged from the chute 14 will be distributed evenly and over a wide area by the plates 15.

Projecting from each end of the enlarged portion 13 of the casing are tubular wings 16, said wings being disposed in longitudinal alignment with each other and communicating with the interior of the casing B. The outer ends of the wings 16 are closed as at 17 and journaled in these closed ends of 85 said wings is a shaft 18 which extends through the enlarged portion 13 of the casing and fixed on the shaft 18 within the enlarged portion 13 is a fan 19 the blades of which are strengthened by braces 20 connecting their free ends. The shaft 18 is connected at one end by a belt 21 with a suitable source of power, while the other end of said shaft 18 is connected by a belt 22 to a shaft 23 journaled in the casing B above the 95 enlarged portion 13. Mounted on the shaft 23 within the casing B is a screw 24 which serves to constantly agitate the fuel which is fed to the casing B through the open upper end 12. Each of the wings 16 is provided in its upper side with an opening 25 controlled by a sliding door 26 whereby the interior of said wings may be placed in communication with the atmosphere to a greater or less extent.

105 The passage of fuel from the upper to the lower portion of the casing B is controlled by a slide valve 27 movable through a slot 28 in the outer walls of the casing B. This valve 27 is provided on its upper 110 side with a lug 29 through which is engaged a lead screw 30 the inner end of said

screw being rotatably mounted in the casing B. By this construction it will be apparent that upon the rotation of the screw 30 in one direction the valve 27 will be moved inwardly of the casing B so as to diminish the flow of fuel from the upper to the lower portion of the casing, while the reverse rotation of said screw will move the valve 27 outwardly of the casing so as to increase the flow of fuel from the upper to the lower portion of the casing.

In the operation of the apparatus fuel is delivered to the casing B through the open upper end 12 thereof. When it is desired to feed the fuel thus delivered to the casing to the furnace the rotation of the shaft 18 is instituted through the medium of the belt 21 and this rotation of the shaft 18 will in turn cause a rotation of the fan 19 and the shaft 23. As the screw 24 rotates with the shaft 23 the fuel will be constantly agitated and forced to the lower part of the casing where it will be acted upon by the fan 19 and blown through the chute 14. As the fuel passes out of the chute 14 it will engage the plate 15 and be distributed thereby in an even manner and over a wide area of the fire box. During the operation of the appa-

ratus the doors 26 are opened sufficiently to allow a desired quantity of air to be drawn in by the fan 19. This air will mingle with the pulverized coal and pass with the latter into the furnace with the result that the combustion of the fuel is maintained at a maximum efficiency.

35

What I claim is:

In a pulverulent feeding apparatus, a fuel supply, a casing communicating with said fuel supply, a discharge chute connected with and leading from the casing, corresponding extensions on each side of the casing having their outer ends closed and their longitudinal walls provided with openings respectively, doors slidably adjustable on the extensions for varying the size of said openings, a shaft journaled transversely of the casing and extending through said extensions, a fan fixed on said shaft for forcing fuel delivered from the supply through the chute, and means for rotating said fan.

40

In testimony whereof, I affix my signature, in the presence of two witnesses.

JOHN H. PORTER.
